CLAIM

The ornamental design for a filtered spray bottle and blender assembly, as shown and described.

DESCRIPTION

FIG. 1 is a top front perspective view of a filtered spray bottle and blender assembly, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a top front perspective view thereof in an alternate condition of use.

The broken lines shown in the drawings depict portions of the filtered spray bottle and blender assembly that form no part of the claimed design.
